UNITED STATES PATENT OFFICE.

WILLIAM M. BRUCE, JR., OF SPRINGFIELD, OHIO, ASSIGNOR, BY DIRECT AND MESNE ASSIGNMENTS, TO THE SELECT TELEPHONE MANUFACTURING COMPANY, OF SPRINGFIELD, OHIO, A CORPORATION OF OHIO.

LOCK-OUT SYSTEM FOR PARTY-LINE TELEPHONES.

No. 833,297.

Specification of Letters Patent.

Patented Oct. 16, 1906.

Application filed October 5, 1905. Serial No. 281,477.

To all whom it may concern:

Be it known that I, WILLIAM M. BRUCE, Jr., a citizen of the United States, residing at Springfield, in the county of Clark and State 5 of Ohio, have invented certain new and useful Improvements in Lock-Out Systems for Party-Line Telephones, of which the following is a specification.

My invention relates to improvements in devices for securing secrecy in party-line telephones, the object being to provide a simple and effective device which can be used with common-battery metallic-circuit telephone systems and without the necessity of 5 ground connections, the arrangement and construction being such that any number of subscribers may be placed on a single line and that when one subscriber removes his telephone for use all the other subscribers will be automatically locked out and cannot use the line or hear the conversation on the line until the subscriber has again released the line by replacing his telephone in normal position.

My invention consists in the arrangement and construction of parts hereinafter described, and pointed out in the claims.

In the accompanying drawing, I have shown a diagrammatic view of a single line to which are attached several subscribers' stations, the line being connected at the central station with the usual switchboard-switch, preferably of the ordinary spring-jack type, the said line being supplied with a common 15 battery through suitable impedance-coils a' and b' . At the several subscribers' stations, e' represents the ordinary telephone-hook; e^2 , an electromagnet or relay placed in a bridge by lines e across the main line a and b , and 20 adapted to receive current from the central energy B whenever the telephone is removed from the hook e' by closing the switch e^3 . I provide around the electromagnet e^2 a shunt-circuit ff , including a push-button or hand-operated switch f^1 , an electric magnetic switch f^2 , operated by the relay or electromagnet e , and the usual subscribers' talking set f^3 . From the hand-operated switch f^1 , which is normally closed, I provide a second 25 connection g to the line a , including a condenser g' . The relay or electromagnet e^2 will preferably be of greater resistance than the talking instrument of the subscriber.

Immediately that the relay operates the shunt-circuit, including the talking instruments, will also be thrown into circuit, and while sufficient current will still flow through the relay to hold the switch f^2 closed there will not be sufficient current on the line to operate any other relay on the line. Hence 55 when one subscriber has removed his hook all the other talking-circuits will be opened and will remain open until the subscriber has replaced his instrument on the hook.

In the event that one subscriber would 60 want to talk to another subscriber on the same line by operating the switch f' the subscribers' talking instruments will be thrown out of the direct shunt-around the relay and will be put in the shunt g , including the condenser. The current from the central energy will thus cease to flow through the subscriber's talking instrument, and thus sufficient current will pass out on the line a to 65 operate any other relay on the line. The first subscriber, however, will be able to hear any conversation on the line through the condenser g' , as the alternating currents produced by the transmitter in the induction-coil of the talking-instrument will pass 70 through the condenser, while the direct current flowing from the battery will not.

The operation of the device is thought to be clear from the above. Any subscriber removing his telephone from the hook establishes a connection by the circuit-closer e^3 through the relay, which is bridged directly across the line. This relay operates the switch f^2 and closes the subscriber's talking instrument in the shunt around the relay. 80 The bringing of the subscriber's instrument into this additional or shunt circuit will absorb so much of the current on the line a that no other relay on the line may be operated. If the subscriber desires to talk 85 with another subscriber on the same line, with his telephone off the hook he signals said subscriber or notifies the operator at the central station to signal him and immediately presses the switch f' . The pressing of the 90 switch opens the shunt f to line a , but closes the shunt through g and the condenser g' , thus cutting out the subscriber's talking instruments from the energy of the battery at the central station, but establishes a shunt 95 through the condenser which will enable the 100 105

subscriber to hear when the other subscriber is on the line, the alternating currents produced by the transmitter passing through the condenser. The pressing of the switch 5 f'' will not affect the holding of the switch f'' by the magnet e^2 , as the bridge containing this magnet is not disturbed by the pressing of the switch f'' , and the stopping of the flow of current through the shunt around this 10 magnet by interposing the condenser g' therein will permit a sufficient amount of current to pass to the other called subscriber to operate his magnet or relay. As soon as the first subscriber hears the other 15 subscriber on the line the switch f'' is closed, thus cutting out the condenser and reestablishing the shunt around the magnet e with the instruments therein. The coming in of the second subscriber will close the shunt 20 around his relay, and thus prevent any other relay from being operated until both of the telephones are again on the hook and the line in normal condition. While the shunt around the relay containing the talking instruments 25 will absorb so much current as to prevent any other relay on the line from being operated, it will not prevent the relay-magnets from holding their armatures in the position into which they have moved, as 30 there will still be sufficient current passing through the relay-magnets to energize the magnets sufficiently to hold them in their closed position, although the electromagnetic force would not be sufficient to move the 35 armature to the closed position if the shunt around the armature had been established prior to the closing of another relay.

Having thus described my invention, I claim—

40 1. In a common party-line telephone system, an electromagnet at each subscriber's station adapted to be bridged across the line by the main telephone-switch, a normally open shunt around said electromagnet including the subscribers' talking instruments, and a circuit-closer in said shunt adapted to be moved to and held in closed position by the electromagnetic force of said magnet and adapted to be released when said magnet is 45 deenergized, the resistance of said magnet and the shunt around the same being such as to absorb the current from the central 50

energy so as to prevent any other magnet on the line from being operated.

2. In a central-energy party-line telephone system, a series of stations including talking instruments, a main switch operated by a telephone-receiver, a relay adapted to be bridged across the line by the operation of said main telephone-switch, a shunt around 55 said relay including the subscriber's talking outfit, and a circuit-closer in said shunt operated by the electromagnetic force of said relay to hold said shunt closed so long as the relay-magnet is energized and to open said 60 shunt when the relay-magnet is not energized, said relay having greater resistance than the shunt around the same, whereby the operation of one relay and the closing of the talking-circuit will prevent the operation 65 of any other relay on the line.

3. In a central-energy party-line telephone system, a series of subscribers' stations, a relay adapted to be bridged across the line by the operation of the main telephone- 70 switch, a normally open shunt around said relay, a circuit-closer operated by the electromagnetic force of said relay to close and maintain the shunt around the relay so long as the relay-magnet is energized and to open 75 said shunt when said magnet is not energized, and talking instruments also adapted to be brought into the circuit by the operation of said relay.

4. In a central-energy party-line telephone 80 system, a series of subscribers' stations, a relay adapted to be bridged across the line by the operation of the main telephone-switch, a shunt around said relay having two branches including the talking instruments, 85 one of said branches going direct to the line and the other branch including a condenser, a circuit-closer operated by the electromagnetic force of the relay to close and maintain the shunt around the relay through either 90 branch, and a switch adapted to establish a shunt through either branch, substantially as and for the purpose specified.

In testimony whereof I have hereunto set my hand this 30th day of September, A. D. 1905.

WILLIAM M. BRUCE, JR.
